UNITED STATES PATENT OFFICE.

HALBERT B. HALVORSEN, OF CHICAGO, ILLINOIS, ASSIGNOR OF ONE-HALF
TO WILLIAM K. MILLHOLLAND, OF SAME PLACE.

ENGINE-GOVERNOR.

SPECIFICATION forming part of Letters Patent No. 593,802, dated November 16, 1897.

Application filed June 25, 1896. Serial No. 596,880. (No model.)

To all whom it may concern:

Be it known that I, HALBERT B. HALVORSEN, of Chicago, in the county of Cook and State of Illinois, have invented certain new and useful Improvements in Engine-Governors; and I do hereby declare that the following is a full, clear, and exact description thereof, reference being had to the accompanying drawings, and to the letters of reference marked thereon, which form a part of this specification.

This invention relates to improvements in steam-engine governors of that class known as "fly-wheel" governors, or those embracing centrifugally-acting weights, which are movably mounted with respect to the shaft and are connected with the eccentric of the engine in such manner as to shift the same laterally on the shaft, together with springs which operate to draw the governor-weight inward in opposition to the centrifugal force by which the same is thrown outward.

The invention consists in the features of construction hereinafter set forth, and pointed out in the appended claims.

In the accompanying drawings, which illustrate my invention, Figure 1 is a view in side elevation of a governor embodying my invention. Fig. 2 is a sectional view thereof, taken on line 2 2 of Fig. 1. Fig. 3 is a sectional view thereof, taken on line 3 3 of Fig. 1. Fig. 4 is a detail section taken on line 4 4 of Fig. 1.

As shown in said drawings, A indicates the crank-shaft, and B the fly-wheel, which is secured thereto.

C indicates the main eccentric, which is engaged with the eccentric-rod of the engine in the usual manner, and D is an internal or secondary eccentric which is located within and forms a support for the main eccentric C and which directly engages the shaft A. Said eccentric D is mounted to turn on the shaft and is given a rotary motion thereon by a suitable connection with the movable governor-weights. The connections between the weights and the eccentric consist, as shown, of rigid arms D' D' on the eccentric, and links d, which connect the said weights with the said arms and which are pivoted to the arms by pivot-pins d' d' and to the weights by pivot-pins d² d², passing through lugs e e on the weights in the manner illus-

trated. Said eccentric D is shown as provided with a sleeve or hub D², which gives it an extended bearing on the shaft and to which the arms D' are attached at their inner ends. The main eccentric is provided with a rigidly-attached supporting-arm C', which extends radially outward therefrom, and the outer end of which is pivotally connected with the wheel by means of a pivot-pin c, herein shown as inserted in the rim or flange of the wheel. Said arm affords lateral oscillatory movement in the main eccentric when the inner supporting-eccentric D is turned, and at the same time holds the said eccentric from turning on the inner eccentric and restrains it from rotary motion relatively to the wheel and shaft. The rotation of said inner eccentric D produces, however, a compound movement of the main eccentric C in a direction both lateral and longitudinal with respect to the arm C', and in order to afford the necessary movement of said main eccentric in a direction longitudinally of the arm the latter is connected with the wheel by a sliding connection, herein shown as formed by means of a slot c² in said arm, through which slot the pin c passes and in which it slides.

The weights E are supported by means of leaf-springs F F, to the central parts of which said weights are connected and which are arranged generally in a direction at right angles to radial lines passing through said weights. Said springs are connected at both ends with the wheel, so that movement of the weights is produced by the flexure of end portions of the springs, by which outward movement is permitted in the middle parts of the springs with which the weights are connected. Attachment of the weights to said springs is conveniently formed by the insertion of the springs through holes in the weights in the manner illustrated. Each of said springs is immovably secured at one end to the wheel and movably secured at its opposite end thereto. This construction enables the ends of the springs to approach each other as the springs are flexed, and also enables the position of the weights with respect to their distance from the axis of the shaft to be changed by adjustment of the movable ends of said springs. As herein shown, one end of each spring is attached to the wheel by

means of a stud G, which is secured in the side face of the wheel and extends therefrom in a direction parallel with the shaft, the end of the spring being bent into an eye or loop e', which embraces said stud, in the manner shown. The opposite or movable end of each spring is movably connected with the wheel by means of a link II, engaged at one end with the pivot-stud G of the opposite spring, 10 and at the other end with the pivot-pin h, by which it is connected with the end of the spring, the spring being provided at this end also with an eye or loop e', through which said pivot-pin passes. Each of said links II 15 is provided with an adjusting device by which its length may be changed, such adjusting device conveniently having the form of a turn-buckle. As shown, the adjusting device consists of screw-threaded shaft II', the ends of 20 which are oppositely screw-threaded and inserted in separated end portions of the link. Said shaft has at its central part a flat-sided collar h', by which the shaft may be turned to adjust the length of the link. The spring 25 F, as shown, is notched at each end, so as to form a central opening in which the ends of the links are inserted. By lengthening or shortening the said links II central parts of the springs F F, with the weights thereon, 30 are brought nearer to or farther from the axis of the shaft and the operation of the governor thereby controlled, as found necessary to secure the desired results in the regulation of the engine to which it is applied.

35 In the operation of a governor constructed as described the weights E are moved inwardly and outwardly, according to the amount of centrifugal force developed by the rotation of the wheels and the resistance of 40 the springs to flexure, said springs obviously tending to hold the weights at the inward limit of their movement in opposition to the centrifugal force, which tends to throw the same outward. When the governor-weights 45 move outwardly, the inner eccentric D is turned in a direction to throw its central point laterally with respect to the supporting-arm C' of the main eccentric or to bring the wider part of the inner eccentric near the wider part 50 of the main eccentric, thereby increasing the eccentricity or throw of the main eccentric. The movement of said weights inwardly or in the opposite direction, on the contrary, tends to carry the wider part of the inner eccentric 55 opposite the narrower part of the outer eccentric and to thereby decrease the throw of said outer eccentric.

The pivotal connection of the links II at both ends with the springs and with the fly-wheel greatly increases the capacity of the 60 springs to flex or bend in a way to allow the outward movement of the weights, it being obvious that as the weights move outwardly the curvature of the springs will increase and their ends will be drawn together, such movement of the free ends of the springs being afforded by the swinging of the links II on the stationary pivots G in an obvious manner.

The device as a whole is exceedingly simple and strong in construction and at the same 70 time sensitive to slight changes of speed in the engine, while the means for adjusting the springs is simple in construction and operation and not liable to get out of order.

I claim as my invention—

1. The combination with a shaft and fly-wheel, of a main eccentric which has laterally-movable but non-rotative connection with the fly-wheel, an inner eccentric mounted to turn on the shaft and to support the main eccentric, a governor-weight pivotally connected with said inner eccentric in such manner as to turn the same when the weight moves inwardly or outwardly and a leaf-spring supporting the weight between its ends, said 80 spring being attached at one end to a pivot-stud rigidly secured to the fly-wheel and attached at its other end to said wheel by means of an endwise-adjustable link pivotally connected with the spring and with the fly-wheel. 90

2. The combination with a shaft and fly-wheel of a main eccentric which has laterally-movable but non-rotative connection with the fly-wheel, an inner supporting-eccentric mounted to turn on the shaft and engaging 95 said main eccentric, said eccentric being provided with a rigidly-attached radial arm, a centrifugally-acting weight connected with said arm and a leaf-spring which engages the weight between its ends, said spring having 100 pivotal connection at one end with said fly-wheel, and a link connecting the opposite end of said spring with said fly-wheel consisting of separate end pieces, and an oppositely-screw-threaded intermediate part connecting 105 the same, said link having a pivotal connection with the spring and fly-wheel.

In testimony that I claim the foregoing as my invention I affix my signature in presence of two witnesses.
